UNITED STATES PATENT OFFICE

JOSEPH B. CRANE, OF NEW YORK, N. Y., AND LEONARD J. MARSHALL, OF WESTWOOD, NEW JERSEY, ASSIGNEES TO INTERNATIONAL COMBUSTION ENGINEERING CORPORATION, OF NEW YORK, N. Y., A CORPORATION OF DELAWARE

HIGH-PRESSURE BOILER INSTALLATION

Application filed September 17, 1928. Serial No. 306,313.

This invention relates to boiler installations to be operated at high pressures and particularly to pulverized fuel fired installations in which the boiler is arranged to be its own furnace in association with a boiler unit adapted to withstand high pressures.

One of the primary objects of the invention is to provide a high pressure boiler unit adapted to be associated with a furnace-shaped boiler which unit is of simple construction, inexpensive to manufacture, capable of withstanding high pressure with safety, and of such arrangement that a superheater and reheater may be very advantageously coordinated therewith.

A specific object of the invention resides in providing a boiler unit of the character described in which relatively thin walled drums, for the high pressure to be carried, may be employed with safety.

Another object of the invention is to provide an arrangement of tubes in a boiler unit of the character described whereby slagging and circulation difficulties are minimized.

More generally it is an object of the invention to provide a relatively simple and effective boiler with superheater and reheater of economical construction, adapted for use in power generating installations employing high pressure and low pressure engine or multistage engines.

How the foregoing, together with such other objects and advantages as may hereinafter appear, or are incident to our invention, are realized is illustrated in preferred form in the accompanying drawings, wherein—

Fig. 1 is a vertical section thru an installation embodying our invention.

Fig. 1a is a fragmentary view illustrating a modification providing a gas offtake at the top.

Fig. 2 is a fragmentary plan section taken on the line 2—2 of Fig. 1 with the parts beyond the plane of the section being omitted.

Fig. 3 is a fragmentary plan section taken on the line 3—3 of Fig. 1 with the parts beyond the plane of the section being omitted.

Fig. 4 is a fragmentary vertical section taken on the line 4—4 of Fig. 1.

Fig. 5 is an enlarged cross sectional view

of the upper drum of the boiler unit shown in Figure 1, and

Fig. 6 is a development of the drum of Fig. 5.

Referring now more particularly to Fig. 1 of the drawings, the installation illustrated comprises, in general, a combustion chamber A, burner means B of any preferred type for introducing finely divided fuel such as pulverized coal into the combustion chamber to be burned in space therein, an ash pit C, and a boiler unit D, adapted to withstand high pressures, located across the offtake E of the combustion chamber.

The combustion space of the boiler is largely defined by steam evaporating surfaces subject to radiant heat. As here shown, the front of the combustion space above the burner means B is defined by a row of boiler tubes 7, the rear, below the boiler unit D, by a row of boiler tubes 8, the sides by the sets of tubes 9 and 10 which are connected together by means of a header 11, and the top by means of a row of tubes 12. The tubes of these rows are preferably finned and they are spaced so that the fins substantially abut. A row of tubes 13 extends across the bottom portion of the combustion chamber and the tubes of this row are spaced sufficiently widely apart to allow gravitating ash to pass thru the space between the tubes into the ash pit C.

The tubes of the bottom row 13 are connected at one end into a header 14 and at the other end into a header 15 and they incline upwardly from the rear to the front of the combustion chamber. The header 15 is connected with a header 16 thereabove by means of tubes 17. The tubes of the front row 7 are connected at their lower ends into the header 16 and at their upper ends into a header 18. The top row of tubes 12 are connected at one end into the header 18 and at the other end into the upper drum 19 of the boiler unit D. The tubes of the rear row 8 are connected at their lower ends into the header 14 and at their upper ends into the lower drum 20 of the unit D.

The boiler unit D comprises, in general, the upper and lower drums 19 and 20 just

referred to, and a plurality of tubes 21 connecting said drums arranged in a manner hereinafter appearing. A drum 22 may be associated with the upper drum 19 to provide relatively dry steam under any conditions of operation, if desired.

The tubes of the set of tubes 9 are connected at their lower ends into a header 23 and at their upper ends into the connecting header 11 and the tubes of the set 10 are connected at their lower ends into the header 11 and at their upper ends into a header 24.

A plurality of downcomer tubes 25 lead water from the drum 20 to the header 14 and from thence the flow is upward thru the tubes 13, 17, 7, 12 to the upper drum 19. The flow also is upward thru the sets of tubes 9 and 10 from the header 14 to the upper drum 19, there being a plurality of tubes 26 provided for connecting the header 14 with the header 23 and a plurality of tubes 27 for connecting the header 24 with the drum 19, the particular arrangement of which will be hereinafter described. The rearward tubes 25 of the connecting tubes 21 act as downcomers from the upper drum 19 to the lower drum 20.

Referring now to the particular construction and arrangement of the unit D, it will be noted that the connecting tubes 21 are arranged in groups and in this instance there is illustrated a front group of three rows of tubes *a*, *b* and *c* which are substantially spaced from a central row of tubes *d* and a rear group of three rows of tubes *e*, *f* and *g*, also substantially spaced from the central row *d*. The first two rows of tubes *a* and *b* are preferably inclined from the vertical so that they lean toward the combustion space, or stated in another way, they incline upwardly toward the combustion chamber. Thus slagging at the upper portions of the tubes where the gases enter the passes of the unit is prevented and a more positive circulation in the tubes is provided because the tendency will be for steam bubbles to rise to the rear of the tubes, i. e., the portion of the tubes away from the combustion chamber, instead of to the front and in this manner the tubes will have greater relieving capacity.

The tubes of the rows *a*, *b* and *c* have their upper portions so disposed that they may be connected into four rows of tube holes in the upper drum, as will be clear from the following description, and the lower portions of these tubes are so disposed that they may be connected into two rows of tube holes in the lower drum, as will be clear from inspection of Figs. 1 and 4 of the drawings.

The tubes of the first row *a* are relatively widely spaced say, for example, on 12 inch centers, and are secured at their upper ends in the similarly spaced holes of the row of holes *a'* in the upper drum and at their lower ends in a row of holes in the lower drum.

The tubes of the second row *b*, however, are more closely spaced say, for example, on 6 inch centers, altho it is to be noted that at their upper portions the tubes divide into two rows, every other tube comprising one row and the remaining tubes comprising the other row. Two rows of tube holes *b'* and *b''* are provided in the upper drum into which the tubes are secured, the holes of one row being staggered with relation to the holes of the other row. By such an arrangement it will be seen that tube ligaments are provided in the drum which are very materially greater than would be provided if the tubes were connected into a single row of holes spaced on 6 inch centers. The tubes of this row at their lower portions are divided into two rows adapting them to be connected into holes in the lower drum alternating with the tube holes for the row of tubes *a* and for the row *c*.

The tubes of the third row *c* are preferably spaced on centers corresponding to the centers of the first row and are secured in a row of holes *c'* in the upper drums, the tubes of the row *c* being staggered with relation to the tubes of the row *a*. The tubes of the remaining rows *d*, *e*, *f* and *g*, are preferably spaced on centers corresponding to the spacing of the first row *a*, and the connecting holes in the upper drum for these tubes are arranged in rows *d'*, *e'*, *f'* and *g'*.

The tubes of the roof wall 12 of the combustion chamber are spaced on relatively close centers, say for example 6 inch centers, and in order to provide substantial tube ligaments where they connect into the upper drum 19 each alternate tube at its end portion adjacent the drum is bent so that they may be connected into two rows of tube holes 12' and 12'' in the drum, the holes of said rows being widely spaced apart and arranged in staggered relation.

The tubes 27 for connecting the headers 24 to the drum 19 also have their end portions adjacent the drum divided into two rows for connection into two rows of tube holes 27' and 27'' which provides an arrangement giving very substantial tube ligaments for the drum. It is pointed out that inasmuch as the holes of the rows 27' and 27'' are not shown arranged in staggered relation the bent portions 27''' of the alternate tubes will, in addition to being bent upwardly, have to bend sidewise to register with holes of the row 27''.

Other rows of holes *h* and *i* are provided in the upper drum for connection of the tubes 21' and 21'' leading from the drum 19 to the drum 22.

From the foregoing it will be seen that an arrangement of tubes and tube holes is provided whereby very substantial tube ligaments are provided in consequence of which relatively thin walled drums may be employed for the high pressures to be carried. It has been found for example that in an in-

stallation designed for 1400 pounds pressure with a 40 inch drum the wall of the drum will safely carry such pressure if it be made as thin as $2\frac{7}{8}$ inches, while heretofore walls as thick as $5\frac{1}{4}$ inches or more had to be employed to ensure safety under similar conditions.

Referring now more particularly to Figs. 1, 2 and 3, it is to be noted that the groups of tubes above referred to each comprise relatively few rows of tubes and relatively few tubes in each row, i. e., the tubes of the rows are widely spaced apart and the rows are also widely spaced apart. A substantial space 28 is provided between the front group of tubes and the central row of tubes *d* in which space a superheater *F* is located and a substantial space 29 is provided between this central row of tubes and the rear group of tubes in which space a reheater *G* is located.

Suitable baffling is provided for the unit to provide a plurality of passes for the gases of combustion thru the unit *D* and in this instance a baffle 30 is arranged at the rear 25 of the front group of tubes which baffle extends from the lower drum 20 to a point short of the upper drum 19, a baffle 31 is associated with tubes of the central row *d* and extends from the upper drum to a point short of the 30 lower drums and a baffle 32 is arranged at the front of the rear group of tubes and extends from the lower drum to a point short of the upper drum. Thus it will be seen that the 35 gases pass downwardly over the superheater, upwardly over the reheater, and then downwardly over and amongst the tubes of the rear group, this last pass being formed in part by the rear wall 33.

Our invention is particularly useful in 40 connection with high pressure steam turbines for the reason that, owing to the small number of tubes employed in the unit *D*, the superheater will be subjected to high heat and the amount of heat abstracted by the 45 tubes of the unit and by the superheater will not be sufficient to reduce the temperature of the gases passing over the reheater to a degree where the reheater will be ineffective for the purpose intended.

50 It will be seen from the foregoing that not only have we provided an arrangement whereby the superheater and reheater will operate effectively but ample space is provided for them and a simple unit is produced 55 which will safely withstand very high pressure without employing thick drums.

The boiler is economical in construction and the drums altho thin walled are relatively small and are, therefore, relatively 60 inexpensive to make.

In Fig. 1a we have illustrated a modification in which a top offtake 33a for the gases is provided. A cross baffle 33b is provided extending from the baffle 32 to rear wall 33.

65 With such an arrangement the rows of tubes

f and *g* act more efficiently as water down-takes.

We claim:

1. In a high pressure boiler installation, a combustion chamber largely defined by radiant heat tubes the amount of evaporating surface of which is such that all of the steaming capacity of the installation is developed thereby; an outlet for said chamber; a relatively small boiler unit in said outlet, said unit comprising an upper and a lower drum each of which is small relative to the pressure carried; a bank comprising a relatively small number of riser tubes connecting said drums, and a second bank comprising a relatively small number of downcomer tubes connecting said drums, said banks being spaced apart; a superheater and a reheater in said space; the amount of evaporating surface presented by said riser tubes being approximately just sufficient to lower the temperature of the gaseous products of combustion to protect the superheater and reheater elements against excessive temperature; and means for introducing the fuel to be burned into the lower part of the combustion chamber.

2. In a high pressure boiler installation, a combustion chamber largely defined by radiant heat tubes the amount of evaporating surface of which is such that substantially all of the steaming capacity of the installation is developed thereby; an outlet for said chamber; a relatively small boiler unit in said outlet, said unit comprising an upper and lower drum each of which is small relative to the pressure carried, a bank comprising a relatively small number of riser tubes connecting said drums, and a second bank comprising a relatively small number of down-comer tubes connecting said drums, said banks being spaced apart, the tubes of the riser bank being arranged in rows in the longitudinal direction of the drums and the upper drum having tube holes for said riser tubes arranged in rows in the longitudinal direction of the drum, there being more rows of tube holes than rows of riser tubes; a superheater and a reheater in the space between said banks, the amount of evaporating surface presented by said riser tubes being approximately just sufficient to lower the temperature of the gaseous products of combustion to protect the superheater and reheater elements against excessive temperature, and means for introducing fuel to be burned into the lower part of the combustion chamber.

3. In a high pressure boiler installation, a combustion chamber largely defined by radiant heat tubes the amount of evaporating surface of which is such that substantially all of the steaming capacity of the installation is developed thereby; an outlet for said chamber; a relatively small boiler unit in said outlet; said unit comprising an upper

and lower drum each of which is small relative to the pressure carried, a bank comprising a relatively small number of riser tubes connecting said drums, and a second bank comprising a relatively small number of 5 downcomer tubes connecting said drums, said banks being spaced apart, the tubes of the riser bank being arranged in rows in the longitudinal direction of the drums and the upper drum having tube holes for said riser tubes arranged in rows in the longitudinal direction of the drum, there being more rows of tube holes than rows of riser tubes; a superheater and a reheater in the space between 10 said banks; the amount of evaporating surface presented by said riser tubes being approximately just sufficient to lower the temperature of the gaseous products of combustion to protect the superheater and reheater 15 elements against excessive temperature; certain of the aforesaid radiant heat tubes having upcomer connection into the upper drum with the points of connection into said drum arranged in such spaced relation as to provide 20 substantial tube ligaments in said drum; and means for introducing fuel to be burned 25 into the lower part of the combustion chamber.

4. In a high pressure boiler installation, 30 a combustion chamber largely defined by radiant heat tubes the amount of evaporating surface of which is such that substantially all of the steaming capacity of the installation is developed thereby; an outlet for said 35 chamber; a relatively small boiler unit in said outlet, said unit comprising an upper and lower drum each of which is small relative to the pressure carried, a bank comprising a relatively small number of riser tubes connecting said drums, and a second bank comprising a relatively small number of 40 downcomer tubes connecting said drums, said banks being spaced apart, the tubes of the riser bank being arranged in rows in the longitudinal direction of the drums and the upper drum having tube holes for said riser tubes arranged in rows in the longitudinal direction of the drum, there being more rows of tube holes than rows of riser tubes; a 45 superheater and a reheater in the space between said banks; the amount of evaporating surface presented by said riser tubes being approximately just sufficient to lower the temperature of the gaseous products of combustion to protect the superheater and reheater 50 elements against excessive temperature; a dry steam drum connected to said upper drum by a plurality of tubes; and means for introducing fuel to be burned into 55 the lower part of the combustion chamber.

In testimony whereof we have hereunto signed our names.

JOSEPH B. CRANE.

LEONARD J. MARSHALL.
